UNITED STATES PATENT OFFICE.

ALEXANDER DURAND, OF LOS ANGELES, CALIFORNIA.

TAILOR'S IRON.

1,219,090.

Specification of Letters Patent. Patented Mar. 13, 1917.

Application filed October 19, 1914, Serial No. 867,550. Renewed November 1, 1916. Serial No. 129,041.

To all whom it may concern:

Be it known that I, ALEXANDER DURAND, a citizen of the United States, residing at Los Angeles, in the county of Los Angeles, State 5 of California, have invented a new and useful Improvement in Tailors' Irons, of which the following is a specification.

My invention relates to tailors' irons and the principal object of the invention is to 10 provide means in such an iron whereby hot water or steam can be mixed and delivered to the goods to be ironed, the amount of water and steam in said mixture being easily and instantly controlled by the operator. 15 Further objects and advantages will be evident hereinafter.

Referring to the drawings which are for illustrative purposes only:

Figure 1 is a plan view of an electric iron 20 equipped with my invention, a portion thereof being shown in section to better illustrate the invention.

Fig. 2 is an elevation of the invention, a portion thereof being shown in section on 25 the plane x^2-x^2 of Fig. 1.

Fig. 3 is an enlarged central section, on the plane x^2-x^2 of Fig. 1, of the valve and a portion of the connecting pipes.

Fig. 4 is a further enlarged section of one 30 of the valve members.

Fig. 5 is a section on the plane x^5-x^5 of Fig. 1 of a portion of the invention.

In the form of my invention illustrated in 35 the drawings, a body portion 10 is provided having a cover 11 which may have suitable heat insulation 9, and on which are formed standards 12 and 13 between which a handle 14 is secured. The body portion 10 is hollowed out as shown at 15 and an electric 40 heating element 16 fed by suitable wires 17 and through flexible wires 18 is placed therein. A backing block 19 is secured by means of screws 20 on top of the electric heating element 16 being suitably insulated 45 therefrom as is the standard practice in electric irons, the backing block serving as a heat storage medium for a portion of the heat generated by the heating element 16. A distributing passage 21 is formed in a rib 50 formed in the extreme toe of the iron, the rib being insulated from the main body of the iron by means of insulating spaces 22. A series of minute perforations 23 extend 55 downwardly from the distributing channel 21 through the face of the iron. A small hole 24 extends upwardly through the extreme point of the iron and a block 25 is

screwed into the upper end thereof, the interior of this block being in open communication with the hole 24. Secured in the 60 block 25 is a water pipe 26 and a steam pipe 27. The water pipe 26 is secured by means of a coupling 28 with a pipe 29 and the steam pipe 27 is secured by means of a coupling 30 with a steam coil 31 which is placed 65 inside the iron resting upon the top of the backing block 19. The steam coil 31 is secured by means of a coupling 32 with a pipe 33. The pipes 29 and 33 pass through the standard 13 and are tightly secured in openings 34 and 35 in a valve body 36, the valve body having an opening at its opposite end in which is secured a water supply pipe 37 which passes through the center of the handle 14 and through the standard 12 and is 70 connected by means of a flexible pipe 38 with any convenient source of water supply. The flexible pipe may be dispensed with and a small water reservoir placed on the handle. The pipe 37 communicates with the center 75 of an internal valve chamber 39 having a water valve 41 in one side thereof and a steam valve 42 in the other side thereof. These valves are manipulated by the thumb and finger of the operator by means of buttons 43 and 44 and are held against their 80 seat by means of a compression spring 45, suitable packing 46 being secured about the valve stems, this packing being compressed by means of followers 47. For purposes of 85 manufacture the valve 42 is mounted in a removable block 48. The valves 41 and 42 are so shaped that when the buttons 43 and 44 press downwardly the pipe 37 is thrown 90 into communication with either or both of the pipes 29 and 33.

The method of operation of the invention is as follows: Electric current being supplied from any convenient source to the heating element 16 and the flexible pipe 38 100 being connected to any convenient source of water supply the operator manipulates the iron in the ordinary manner, pressing the goods upon which he works. For the purpose of thoroughly pressing fabrics it is 105 desirable to supply either water or steam or both, the amount of moisture and its condition being governed both by the condition of the iron and the character of the goods. For example, with a very hot iron a different amount of moisture in a different condition is necessary than with a relatively cool iron. When the operator desires to 110 supply water to the face of the goods he

presses downwardly upon the button 43 and allows water to flow into the pipe 29 and from thence into the pipe 26 and downwardly through the opening 24 into the distributing channel 21, and from thence through the small holes 23 upon the goods to be pressed. When the operator desires to supply steam to the face of the goods he presses upwardly upon the button 44 therefore by connecting the pipe 37 with the pipe 33 and allowing water to flow through the heating coil 31 which is in contact with the hot backing block 19 of the iron, the water being changed to steam in its passage through the steam coil and emerging from the openings 23 in the form of a jet of steam. When the operator desires he can admit both water and steam simultaneously in any proportion which he desires. This is an important feature of the invention as the amount and character of the moisture are so dependent on the kind and condition of goods to be pressed that an accurate control of this feature is indispensable to a perfectly operating iron.

I claim as my invention:

1. A tailor's iron comprising a heating means, a water supply means, a steam generating means in contact with said heating means, and means whereby water can be passed through the steam generating means to the toe of the iron and also directly to the toe of the iron without passing through said steam generating means.

2. A tailor's iron comprising a body portion, a rib formed at the forward end of said body portion having a distributing channel therein, said channel having minute openings communicating with the face of the iron, a water supply means, a cover for said body portion having standards formed thereon, a handle secured between said standards, a heating means, a steam coil so placed as to be heated by said heating means, and valve means in said handle whereby said water supply means can be connected to said channel through said steam coil.

3. A tailor's iron comprising a body portion, a rib formed at the forward end of said body portion having a distributing channel therein, said channel having minute openings communicating with the face of the iron, a water supply means, a cover for said body portion having standards formed thereon, a handle secured between said standards, a heating means, a steam coil so placed as to be heated by said heating means, and valve means in said handle whereby said water supply means can be connected to said channel both directly and through the steam coil.

4. A tailor's iron comprising a body portion, a rib formed at the forward end of

said body portion having a distributing channel therein, said channel having minute openings communicating with the face of the iron, a water supply means, a cover for said body portion having standards formed thereon, a handle secured between said standards, a heating means, a steam coil so placed as to be heated by said heating means, and valve means in said handle whereby said water supply means can be connected to said channel both directly and through the steam coil and whereby the proportion of water passing through the steam coil and directly to said channel can be regulated.

5. A tailor's iron comprising a body portion, a rib formed at the forward end of said body portion having a distributing channel therein, said channel having minute openings communicating with the face of the iron, a water supply means, a cover for said body portion having standards formed thereon, a handle secured between said standards, a heating means, a steam coil so placed as to be heated by said heating means, a valve body having a central opening in direct communication with the water supply means and having outlet openings in one end in open communication with said steam coil and said channel, and means whereby the flow of water between said central opening and the said outlet openings can be regulated and controlled.

6. A tailor's iron comprising a body portion, a rib formed at the forward end of said body portion having standards formed channel therein, said channel having minute openings communicating with the face of the iron, a water supply means, a cover for said body portion having standards formed thereon, a handle secured between said standards, a heating means, a steam coil so placed as to be heated by said heating means, a valve body having a central opening in direct communication with the water supply means and having outlet openings in one end in open communication with said steam coil and said channel, a steam valve in said central opening arranged to control the flow of water from said supply means to said steam coil through one of said outlet openings, and a water valve in said central opening arranged to control the flow of water from said supply means to said distributing channel to the other of said outlet openings.

In testimony whereof, I have hereunto set my hand at Los Angeles, California, this 12th day of October, 1914.

ALEXANDER DURAND.

In presence of—

FRED A. MANSFIELD,
FORD W. HARRIS.
